by his Atty, M. L. L. & Son

United States Patent Office.

WILLIAM WINCHESTER, OF PORTLAND, MAINE, ASSIGNOR TO HIMSELF, GEORGE F. MCLELLAN, AND JAMES T. BENEDICT, OF WASHINGTON, DISTRICT OF COLUMBIA.

Letters Patent No. 94,804, dated September 14, 1869.

IMPROVED PURCHASE FOR HOISTING AND LOWERING TOP-MASTS OF VESSELS.

The Schedule referred to in these Letters Patent and making part of the same.

Be it known that I, WILLIAM WINCHESTER, of Portland, in the county of Cumberland, and State of Maine, have invented a new and improved Tackle for Hoisting and Lowering the Top-Masts of Vessels; and I do hereby declare that the following is a full and exact description thereof, reference being had to the accompanying drawings, and the letters of reference marked thereon.

Figure 1 is a rear elevation of mast with top-mast partly hoisted.

Figure 2 is a side elevation of mast with top-mast hoisted to its place.

Figures 3 and 4 are views of combination block E. A is mast of vessel.

B is top-mast of vessel.

b is mortise through lower end of top-mast.

C is top of mast.

D is cap of mast.

D' D' are sheaves inserted in mortises in lower end of top-mast B.

d is a bolt passing through the top of the mast and the cap, with eye in lower end.

E is block, to be connected with bolt by eye.

e e e are sheaves in block E.

F is rope passing through block E and over sheaves D' D'.

G is a double block, attached to an end of rope F.

H is a double block, through which rope I passes, and to be fastened to deck of ship.

I, rope passing through blocks G and H.

To enable others skilled in the art to make and use my invention, I will proceed to describe its construction and operation.

The ordinary method of hoisting top-masts is by common blocks and tackle, one block being attached to one side of the upper part of mast, and the other to one side of lower end of top-mast. In this way the top-mast is made to turn on its axis, and before it can be sent home it must be turned back again, and usually this requires the labor of many men for an hour or more.

My invention is intended to obviate this difficulty, so that the top-mast can be sent up without danger of being caught on the way, and, if turned, it will right itself without help.

I make the triple block E with the sheaves inserted at a bevel with the sides of the block, substantially as represented in the drawings. This block is secured to top of the mast by the bolt d, which passes through the middle of the top D, and is held in place by means of a nut and a pin running through the bolt over the nut.

Through the lower end of top-mast B, I make mortises, bevelled as in the drawings, in which I secure the sheaves D' D'. Then over these sheaves, and through the block E, I reeve the rope F, the end of which, passing over the lowest sheave in the block E, is fastened to the block G.

Through blocks G and H, I reeve rope I, securing block H to deck of ship.

The top-mast then being placed in position, the end of rope I is made fast, and, by hauling on rope F, the top-mast is carried nearly to its proper place. Then, by hauling on rope I, the end of rope F being made fast, it is sent home, and, by a pin inserted in mortise b, is held there.

By means of my invention the strain comes directly upon the centre of the top-mast, and on the centre of corresponding side of the mast, so that if turned by accident it will necessarily be turned back, and must go fairly home. Then, by placing the sheaves in the block E, and top-mast at D' D' on the bevel, a part of the strain on the rope is relieved, and a more direct action is secured.

What I claim as my invention, and desire to secure by Letters Patent, is—

1. The bolt d, inserted through cap D at place indicated, combined with block E, rope F, bevelled mortises and sheaves D' D' in top-mast B, blocks G and H, and rope I, all arranged and operating substantially in the manner and for the purposes set forth and described.

2. The block E, with two or more sheaves, the sheaves being inserted on bevel, as represented.

WILLIAM WINCHESTER.
